DESIGN FOR A BURIAL CASE HANDLE

John Jamieson, Garfield Heights, Ohio, assignor to The Dickey-Grabler Company, Cleveland,
Ohio, a corporation of Ohio

Application March 28, 1936, Serial No. 61,836

Term of patent 7 years

To all whom it may concern:

Be it known that I, John Jamieson, a citizen of the United States, residing at Garfield Heights, in the county of Cuyahoga and State of Ohio, have invented a new, original, and ornamental Design for Burial Case Handles, of which the following is a specification, reference being had to the accompanying drawing forming part hereof, and wherein Fig. 1 is a front elevation of a burial case handle, showing my new design; Fig. 2 is a plan view thereof, and Fig. 3 is an end elevation.

The essential and dominant feature of the design is shown in solid lines.

I claim:

The ornamental design for a burial case handle as shown and described.

JOHN JAMIESON.
